UNITED STATES PATENT OFFICE.

HARRY J. CALDWELL, OF ROCKFORD, ILLINOIS, ASSIGNOR TO THE INGERSOLL MILLING MACHINE COMPANY, OF ROCKFORD, ILLINOIS, A CORPORATION OF ILLINOIS.

FEED-CONTROL MECHANISM FOR RECIPROCATING-TYPE MACHINES.

Application filed October 17, 1921. Serial No. 508,374.

This invention relating to mechanism for imparting movement to a traveling support, such as a work-carrying table, and for automatically controlling movements of the table, is an improvement on the invention disclosed in my companion application, Serial No. 508,375, filed Oct. 17, 1921. Said application discloses novel mechanism for feeding a work-carrying table at relatively fast and slow speeds in both directions in any of various continuous cycles according to the location of cam dogs on the table which actuate change-speed and reversing devices for obtaining the several feed movements. In said application, the change-speed device and the reversing device is each actuated by a separate set of cam dogs and operating connections, whereas in the present invention a single set of cam dogs actuates a movement-train for effecting both change in speed and direction of travel of the table.

The primary object of the present invention is therefore, to simplify and improve a feed and control mechanism of the character described.

Another object is to provide a feed and control mechanism in which the feed of the reciprocating table or other traveling support may be controlled with greater accuracy and precision.

Other objects and attendant advantages will be appreciated by those skilled in this art as the invention becomes better understood by reference to the following description when considered in connection with the accompanying drawings, in which—

Figure 1 is a front elevation of a reciprocating type milling machine embodying my invention;

Fig. 2 is a fragmentary plan view taken substantially on the line 2—2 of Fig. 1;

Fig. 3 is a horizontal section through the gear box containing the change-speed and reversing clutches;

Fig. 4 is a section through the gear box taken substantially on the line 4—4 of Fig. 3;

Figs. 5 to 8 inclusive, are diagrammatic views illustrating successive positions of the work table and the action of the cam dogs;

Fig. 9 is a development of the cam dog and roller cycle;

Figs. 10 and 11 are related diagrammatic views showing the positions of change-speed and reversing clutches and the control parts

therefor, in one of the rapid reverse positions;

Figs. 12, 13 and 14 are similar related diagrammatic views in a table-feed position; and

Figs. 15—16 and 17—18 are similar groups of related diagrammatic views showing different positions of the table-feed mechanism and control mechanism, which will be more fully explained hereinafter.

In the present example, my invention is illustrated in connection with a reciprocating type milling machine, that is one in which the work is carried on a table which moves back and forth past the cutting tool or tools. My invention has reference to the mechanism for feeding the work table or the equivalent back and forth at relatively fast and slow speeds during each stroke and preferably in a continuous cycle comprising rapid traverse and feed movements in both directions, and it has further reference to the means actuated by cams on the table for controlling the feed mechanism. It should be understood, however, that my improvements are generally applicable to the operation or control of any work or tool carrier which moves back and forth.

The frame of the present machine comprises an elongated bed 21 upon which a work table 22 is mounted to reciprocate horizontally. The bed and table are of conventional construction, the table being mounted on the usual flat bearings and being propelled by means of a screw 23 held against axial translation on the bed and engaging a nut 24 carried by the table. In the present example, a vertical cutter spindle 25 mounted on an overhead frame 26 supported by side housings 27 carries a milling cutter 28. The side housings are positioned midway between the ends of the bed so that the work table can be conveniently loaded when at either end of the bed. It should be understood, however, that a plurality of cutters might be employed mounted at any desired position on the side housings or top frame and that the illustration of a single vertical cutter is simply one example for the purpose of showing a complete cycle of operation and the advantages of the present construction.

My invention contemplates the provision of suitable mechanism for revolving the table-propelling screw at different speeds

and for reversing the screw; also the provision of novel means operated by a single dog or cam-actuated element for controlling the movement of both the change-speed and reversing devices. In the present example, the table is propelled by a train of gearing including change-speed and reversing clutches. In practice, the clutches and the immediate gearing are contained in a gear box or housing 29. This gear box and the enclosed gearing and clutches are preferably constructed as a unit assembly adapted to be applied to different machines of the character in mind and at different positions thereon. In the present case, the gear box is bolted to the rear wall of the bed 21 adjacent to one end of the latter. A driving shaft 31 and a driven shaft 32 journaled in the gear box are connected by intermediate gearing which will be presently described. Any suitable means may be employed for driving the shaft 31, such for example as a belt-driven pulley 33 adapted to be connected to the shaft through the agency of a clutch 34 which may be shifted from the front of the machine by operation of the lever 35. The driven shaft 32 is connected to the screw 23 through the agency of suitable change-speed reduction gears (not shown) in the housing 30. In operation, the driving shaft 31 revolves continuously in one direction and through the agency of the gearing and clutches between the driving and driven shafts, the latter will be driven in opposite directions and at different speeds for correspondingly propelling the work table 22. As shown in Figs. 3 and 4, there is loose on the driving shaft 31, a pair of opposed bevel gears 36 and 37, and an intermediate clutch element 38 splined on the shaft and adapted to be shifted in either direction for connecting its clutch teeth with the complementary teeth on the respective bevel gears 36 and 37. An intermediate bevel gear 39 meshes with both the gears 36 and 37 and is fixed to a worm shaft 41 which carries a fixed worm screw 42. The shaft 41 also carries a fixed bevel gear 43 meshing with a bevel gear 44 fixed to an intermediate shaft 45, to which is fixed a spur gear 46 meshing with a spur gear 47 loose on the driven shaft 32. A friction element 48 is interposed between the shaft 45 and gear 46 for absorbing sudden shocks or strains when the speed is suddenly stepped up. The worm screw 42 meshes with a worm gear 49 loose on the driven shaft 32. The clutch element 51 splined on the shaft 32 is adapted to be shifted in opposite directions to engage the clutch teeth at its ends with complementary teeth on the gears 47 and 49. A rock shaft 52 carries a lever 53 within the gear box, one end 54 of which lever is forked and in operative connection with the clutch element 51 for shifting the latter,

and the opposite end carries a spring-pressed plunger 55 having a pointed head, the faces 56 and 57 of which are respectively adapted to co-operate with a stationary roller 58, as will be presently described. A rock shaft 59 carries a forked arm 61 operatively engaging the clutch element 38 for shifting the latter, and likewise carries a spring-pressed plunger 62, the surfaces 63 and 64 of which are adapted to respectively engage the stationary roller 65, as will be presently described.

From the foregoing, it will be evident that when the driving shaft 31 is rotated in a clockwise direction viewing the right hand side of Fig. 3, with the clutches as shown therein, the shaft 32 will be driven in a similar direction through the agency of gears 36, 39, 43, 44, 46 and 47 at the rapid traverse speed. The worm gear 49, will however, be revolved in the opposite direction by reversal through the worm screw 42. If the clutch element 38 be shifted to connect the gear 37 to the driving shaft without shifting the clutch element 51, the rapid traverse drive will obviously be reversed. By shifting the clutch element 51 to the opposite position the worm gear 49 will be connected to the driven shaft 32 and the latter will be driven at the slow or feed speed in a counter-clockwise direction, because of the fact that the worm wheel 49 revolves in the opposite direction from the rapid traverse gear 47. If however, both clutch elements 38 and 51 are simultaneously thrown to the right the worm wheel 49 will be reversed and the shaft 32 will be driven in the same direction (clockwise) as previously driven by the gear 47, but at a reduced speed. This distinction is noted at this point, because as will be explained later, the clutch elements are shifted simultaneously from a single cam dog and through a single motion-train or connection.

The mechanism for operating the rock shafts 52 and 59, and consequently the clutches, will now be described. A bell-crank lever 66 pivotally mounted on one of the side housings 27 at present adjacent to the rear side of the work table, carries a roller 67 adapted to be actuated by cam dogs 68, 69, 71 and 72, and is connected by a rod 73 to an arm 74 fixed to the rock shaft 52 described above. More particularly, the rod 73 is slidable lengthwise in a sleeve 75 which is pivotally connected on a vertical axis to the outer end of the arm 74. The rod 73 carries a pair of adjustable abutments 76 and 77 between the latter of which and the sleeve 75 are interposed coil compression springs 78 and 79, as shown in Fig. 2. Means is now provided operable between the rock shafts 52 and 59, whereby the latter will be oscillated at every alternate oscillation of the former for a pur-

pose which will be presently apparent. This means comprises a pair of bell cranks 81 and 82, the former of which is fixed to the rock shaft 59 and the latter to a stationary pivot 83, and the arms 84 of which are connected and held in parallel relation by a link 85. The other arms 86 of the levers 81 and 82 are provided respectively with up-standing lugs 87 and 88. These lugs are adapted to be independently engaged by a hooked member 89 pivotally connected to the above mentioned arm 74. Flat springs 93 and 94 carried by the link 85 are respectively adapted at certain times in the operation to urge and hold the hooked end of the member 89 in connection with either one or the other of the lugs 87 and 88.

The operation is as follows: Referring to Figs. 5, 10 and 11, which show an assumed position of related operated parts, it will be observed that the dog 68 has just moved the roller 67 upwardly to the plane 95 and thereby moved the clutch elements 51 to the position shown in Fig. 11, causing the table to be propelled to the right viewing Figs. 5 and 10, in the rapid traverse movement. At the time the roller 67 was actuated to produce this movement the cutter 28 had completed milling a work-piece 96, and during the milling of this work-piece an unfinished work-piece 97 has been mounted on the opposite end of the table. In this position the clutch elements 38 and 51 are held engaged by the action of their respective spring plungers 62 and 55 co-operating with the stationary rollers 65 and 58. It will be observed that in this position the hooked member 89 is connected with the lug 88 and held so by the spring 94. As the table travels to the right at a rapid speed for bringing the work-piece 97 to the cutter 28, the roller 67 which is disposed in the path of the upper end of the dog 69 will be forced upwardly by said dog to the clearance position indicated by dotted lines in Fig. 6 for clearing said dog in an idle movement. This dog-clearance movement is compensated for by compression of the spring 79 without disturbing the position of the clutch. The spring 79 will return the roller 67 to the plane 95 in position to be engaged by the next following dog 71. This dog 71 will move the roller 67 downwardly to the plane 98 as shown in Figs. 6 and 12 for the purpose of reducing the travel of the table to the slow speed or feed just prior to the time the work-piece 97 reaches the cutter. The dog 67 in being moved to this position will compress the spring 78 and carry the abutment 76 into contact with the adjacent end of the sleeve 75, thereby withdrawing the clutch element 51 from the rapid traverse gear 47 and likewise withdrawing the clutch element 38 from the gear 36. This movement is not sufficient, however, to throw

the plunger levers 53 and 61 beyond the dead-center positions with relation to their respective rollers 58 and 65, and the pressure stored up by the compressed spring 78 is utilized to move the sleeve 75 to the right viewing Fig. 12, on the rod 73, thereby swinging both levers 53 and 61 beyond said dead-center positions, whereupon the spring-pressed plungers carried by said levers will function together with the pressure of the spring 78 for engaging the clutch elements with the gears 37 and 49, as shown in Fig. 14. This establishes slow speed or feed in the same direction. It will be noted that this action by the cam dog 71 causes both clutch elements 38 and 51 to be simultaneously shifted by a single motion-train, it being observed that the hooked member 89 is held in connection with the lug 88, thus establishing operating connection between both clutches. "Motion train" is used herein as meaning a mechanical train of parts through which motion is adapted to be transmitted from an operating part to one or more operated parts, at present the operating part being a bell crank lever adapted to be actuated by one or more cam dogs on a traveling support or work table and the operated part or parts being one or more clutch shifters included in a table propelling mechanism. The feed continues to the right until the work table reaches the position shown in Figs. 7 and 15, when the roller 67 will be moved upwardly by the cam dog 72, thereby shifting only the clutch element 51 to connect the gear 47 to the driven shaft for effecting rapid reverse of the table. It will be observed that in this operation the hooked member 89 has been swung clear of the lug 88 and into engagement with the lug 87, aided by the spring 93, this without disturbing the position of the clutch element 38, so that upon the next succeeding operation of the clutch operating motion-train, the clutch element 38 will be shifted. It will also be observed that in this operation, as in every clutch shifting operation, either the spring 78 or 79 as the case may be, functions to throw one or both of the plunger-carrying levers 53 and 61 past the dead-center positions, and that said springs permit the roller 67 to clear the ends of the dogs in idle clearance movements. While the work-piece 97 was being milled, a new work-piece 96' will have been loaded onto the opposite end of the table. The rapid reverse effected by the dog 72, or rather the rapid traverse to the left, continues until the work-piece 96' reaches the cutter as shown in Fig. 8, whereupon the roller 67 will be moved downwardly by the cam dog 69, thereby moving the clutch operating motion-train to shift both clutches as shown in Figs. 17 and 18, to effect speed reduction or the feed of the table. By this action of the

cam dog 69, both clutch elements 38 and 51 will be shifted, it being observed that the hooked member 89 operates in this instance on the lug 87 and thereby shifts the clutch element 38 in the opposite direction from the operation explained above, with reference to the lug 88. The feed continues until the cam dog 68 effects rapid reverse as shown in Figs. 5, 10 and 11 by shifting only the clutch element 51. This completes the cycle, which will be continuously repeated until the operator throws out the driving clutch 34.

Attention is now directed to the operation of the motion train between the dog-operated roller 67 and the clutches. It will be observed that the changes in speed and reversal of drive are effected through operation of this single motion-train by successive back and forth movement of the roller by the cam dogs. At each operation of the roller, however, both clutches are not operated. By reason of the action of the intermittent connection device between the rock-shafts 52 and 59, the clutch elements 38 will be shifted only upon each alternate shifting of the clutch element 51. That is, as explained above, only the clutch element 51 is shifted when effecting rapid reverse; whereas both clutch elements are shifted to obtain speed reduction to the feed in the same direction of travel as the rapid traverse. By reason of a feed control mechanism embodying the principles disclosed herein, the change-speed and reversing movements in a table propelling mechanism may be controlled by a single set of cam dogs or the equivalent, consequently not only simplifying the construction but also enabling greater accuracy in control of the table movement. While precision in the limits defining the rapid traverse and feed movements is not always essential in machines of this character, nevertheless, in some classes of work, such for example as illustrated diagrammatically by the work-pieces 96 and 97, in which the feed must be stopped at a given point to prevent interference of the cutter with an upstanding or obstructing portion of the work-piece, it is very essential that the reversing and change-speed mechanism be controlled in a positive manner and so that injury to the machine or parts will not result by carelessness or mistake in setting the cam dogs, or parts of the control mechanism.

It is believed that the foregoing conveys a clear understanding of the invention, and while I have illustrated but a single working embodiment it should be understood that considerable change might be made in construction and arrangement without departing from the spirit and scope of the invention as expressed in the appended claims.

65 I claim:—

1. Control mechanism of the character described comprising a traveling support mechanism for propelling the support at different speeds and in different directions, a motion-transmitting part adapted to be moved back and forth in a single plane by movement of said support, and means operated by such movement of said part for controlling the operation of said propelling mechanism to effect each change of direction and change of speed in each direction.

2. The combination of a traveling support, mechanism for moving the support back and forth in a continuous cycle at rapid traverse and feed speeds in both directions including a change-speed and a reversing device, and a motion-train connected with said devices and operated by a part movable back and forth in a single plane by the traveling support for operating both said change-speed and reversing devices to effect reversal of the drive and increase in speed when moved in one direction and reduction of speed when moved in the opposite direction.

3. Feed control mechanism comprising a traveling support, reversing and change-speed clutches for propelling the support, cam dogs on the support, and a motion-train actuated by a single-part adapted to be moved in one direction in a given plane by said dogs for operating said clutches to effect rapid reverse of the support at each end of its travel and to be moved in the opposite direction in said plane by said dogs for operating said clutches to effect reduction of the speed of the support during travel thereof in both directions.

4. Feed control mechanism comprising a traveling support, mechanism for propelling said support including a change speed clutch and a reversing clutch, cam dogs on the support, and a motion-train having a single operating part adapted to be actuated by said dogs for shifting one of said clutches at each actuation by the dogs and for shifting the other clutch with the first clutch at each alternate dog action.

5. Feed control mechanism comprising a traveling support adapted to be moved back and forth in a continuous cycle characterized by rapid reverse at each end of its travel and reduction to feed speed during its travel in each direction, mechanism for propelling said support including a change-speed device and a reversing device, cams on said support, and a single element for operating both said devices adapted to be moved in a single plane by said cams in one direction for effecting said rapid reverse and in the opposite direction said speed reduction.

6. Feed control mechanism of the character described comprising a table adapted to be moved back and forth, mechanism for propelling said table including a change speed clutch

- and a reversing clutch, and a motion-train having a single operating element controlled by movement of said table, said motion-train being connected with both of said clutches for operating one of the clutches at each operation of the motion-train and the other clutch with the first clutch at each alternate operation thereof.
7. The combination of a traveling support, a pair of inclined cam dogs on said support, a single element adapted to be moved back and forth in a single plane by said cam dogs, and mechanism operated by said single element for increasing the speed and changing the direction of travel upon movement of said element in one direction in said plane and reduction of speed upon movement of said element in the opposite direction in said plane.
- 10 8. The combination of a traveling support, a pair of inclined cam dogs on said support, a single element adapted to be moved back and forth in a single plane by said cam dogs, and mechanism operated by said single element for increasing the speed and changing the direction of travel upon movement of said element in one direction in said plane and reduction of speed upon movement of said element in the opposite direction in said plane, said cam dogs being arranged to move said element back and forth once during travel of the support in each direction.
- 15 9. Feed control mechanism of the character described comprising a traveling support adapted to be moved back and forth, cam dogs on the support, an element adapted to be moved back and forth in a single plane by said cam dogs, and mechanism including a change-speed device and a reversing device operated by said element for effecting rapid reverse of the traveling support upon movement of the element in one direction and reduction of speed when moved in the opposite direction.
- 20 10. Feed control mechanism of the character described comprising a traveling support adapted to be moved back and forth, cam dogs on the support, an element adapted to be moved up and down by said cam dogs, and mechanism including a change-speed device and a reversing device operated by said element for effecting rapid reverse of the traveling support upon movement of the element in one direction in said plane and reduction of speed when moved in the opposite direction in said plane, said cam dogs comprising end dogs for effecting said rapid reverse and intermediate dogs for effecting said speed reduction.
- 25 11. Feed control mechanism of the character described comprising a table, mechanism for feeding the table back and forth at rapid traverse and feed speeds during both strokes, cam dogs on the table, an element
- adapted to be moved in a single plane in opposite directions by said dogs, and means including a change-speed device and a reversing device operated by said element by movement of the latter in one direction to produce said rapid traverse and feed speeds during the forward stroke of the table and in the opposite direction for producing said rapid traverse and feed speeds during the reverse stroke.
- 30 12. Feed control mechanism of the character described comprising driving mechanism including a shiftable reversing clutch element and a change-speed clutch element, a traveling support adapted to be moved back and forth by said mechanism, cams on said support, a single element adapted to be actuated by said cams, and means actuated by said cam element by movement thereof in one direction to engage both of said clutch elements to move said support at one speed in one direction and by movement in the opposite direction for moving only one of said clutch elements to change the speed of said support in the same direction of travel.
- 35 13. Feed control mechanism of the character described comprising in combination with a traveling support adapted to be moved back and forth, mechanism including change-speed and reversing clutches for moving said support back and forth at different speeds, cams on said support, and a motion-train having an operating element adapted to be operated by said cams for movement in one direction to operate one of said clutches for reversing the travel of said support at rapid traverse speed and in the opposite direction for simultaneously operating both clutches for moving said support at a reduced speed in the same direction of travel.
- 40 14. Feed control mechanism of the character described comprising a traveling support adapted to be moved back and forth, a driving and a driven shaft, gearing between said shafts including a reversing clutch and a change-speed clutch, a connection between the driven shaft and said support for propelling the latter, cam dogs on said support, and a member adapted to be moved in a single plane in one direction by said cam dogs for operating said clutches to produce rapid reverse of said support at each end of its travel, and to be moved in the opposite direction by said cam dogs for operating said clutches to reduce the speed of said support in the same direction of travel.
- 45 15. Control mechanism of the character described comprising a traveling support, mechanism for propelling it at different speeds and in different directions including a change-speed device and a reversing device, cam dogs on the support, and mechanism including a part adapted to be moved back and forth in a single plane by said cam dogs

and connected with said propelling mechanism for transmitting movement thereto for controlling the operation of both said devices as to speeds and direction of travel.

16. Control mechanism of the character described comprising a traveling support, mechanism for propelling said support including change-speed and reversing means, cam dogs on the support, and means operative between said cam dogs and said mechanism, including a single part adapted to be moved back and forth in a single plane by said cam dogs for effecting changes in speed and direction of travel of said support.

17. In control mechanism, the combination of a traveling support, mechanism for propelling it including a change-speed device and a reversing device, and means including a single operating part actuated by movement of the support for operating one of said devices at each actuation and the other device with the first device at each alternate actuation.

18. In combination, a traveling support, propelling mechanism therefor including a change speed clutch and a reversing clutch, and a motion-train having at one end a single operating part movable back and forth in a single plane and at the opposite end a clutch shifter for each clutch adapted to be shifted in predetermined relative relation by said back and forth movement of the operating part in said single plane.

19. In control mechanism, the combination of driving mechanism including a change-speed clutch and a reversing clutch, one of which drives through the other, and a motion-train for shifting said clutches including an operating member movable back and forth in a single plane for shifting one of the clutches upon movement in one direction and for shifting both clutches upon movement in the opposite direction.

20. In control mechanism the combination of a traveling support, mechanism for propelling it including a change-speed clutch and a reversing clutch, cam dogs on the support, and means for shifting said clutches including a part adapted to be moved back and forth in a single plane by said cam dogs for shifting both clutches when moved in one direction and only one clutch when moved in the other direction.

21. Control mechanism of the character described comprising in combination with

a traveling support and mechanism for propelling it including a change-speed clutch and a reversing clutch, means for shifting said clutches including a part adapted to be moved back and forth in a single plane by movement of the support for shifting both of said clutches when moved in one direction and for shifting only one of the clutches when moved in the other direction.

22. In control mechanism, the combination of a traveling support, mechanism for propelling it at different speeds and in different directions, and means for controlling said mechanism including a part adapted to be moved back and forth in a single plane by movement of the support for controlling the operation of said mechanism to effect change in direction of travel of the support and change of speed in each direction.

23. The combination of a traveling support, mechanism for propelling it at different speeds and in different directions, a cam dog on each end portion of the support, one or more intermediate cam dogs, and means including a part operable in a single plane adapted to be actuated by said cam dogs for controlling said mechanism, the end cam dogs being adapted for moving said part in said plane and the intermediate cam dogs for moving it in the opposite direction in said plane, and said means being constructed for so operating said mechanism as to cause the support to be propelled at a different speed and reversal in direction when actuated by said end dogs and at a different speed only when actuated by said intermediate dogs.

24. The combination of a traveling support, mechanism for propelling it including a change speed clutch and a reversing clutch, a plurality of cam dogs on the support, a bell crank lever mounted so that one arm is adapted to be moved back and forth by said cam dogs, a rod pivotally connected to the arm, a shifter for each clutch, a compensating connection between said rod and one of the shifters permitting the cam-operated end of the bell crank to ride over one or more of said cam dogs in a clearance action without operating said shifter, and a connection between the shifters of both clutches whereby one will be shifted at each alternate shifting of the other.

HARRY J. CALDWELL.

Certificate of Correction.

It is hereby certified that in Letters Patent No. 1,599,204, granted September 7, 1926, upon the application of Harry J. Caldwell, of Rockford, Illinois, for an improvement in "Feed-Control Mechanism for Reciprocating Type Machines," errors appear in the printed specification requiring correction as follows: Page 5, line 50, claim 10, for the words "up and down" read *back and forth in a single plane*; page 6, line 84, claim 23, after the word "part" insert the words *in one direction only*; and that the said Letters Patent should be read with these corrections therein that the same may conform to the record of the case in the Patent Office.

Signed and sealed this 5th day of October, A. D. 1926.

[SEAL.]

M. J. MOORE,
Acting Commissioner of Patents.
